COMBINED VALANCE, LOCK AND HANDLE SUPPORT FOR LUGGAGE OR THE LIKE

Edward M. Stolarz, Yorktown Heights, N.Y., assignor to
Presto Lock Company, Division of Walter Kidde &
Company, Inc., Elmwood Park, N.J.

Filed Nov. 5, 1974, Ser. No. 521,041

Term of patent 14 years

Int. Cl. D3—99

U.S. Cl. D87—5 R

FIG. 1

FIG. 3

FIG. 2

FIG. 4

FIG. 5

FIG. 1 is a top plan view of a combined valance, lock and handle support for luggage or the like embodying my new design;

FIG. 2 is a right side elevational view thereof, the left side elevational view being a mirror image thereof;

FIG. 3 is a front elevational view, the rear elevational view being a mirror image thereof;

FIG. 4 is a bottom plan view; and

FIG. 5 is a fragmentary bottom plan view taken in the direction of line 5—5 of FIG. 3.

I claim:

The ornamental design for a combined valance, lock and handle support for luggage or the like, as shown and described.
